UNITED STATES PATENT OFFICE.

OTTO SCHALLER, OF STEGLITZ, NEAR BERLIN, GERMANY, ASSIGNOR TO
THE FIRM OF JULIUS PINTSCH, OF BERLIN, GERMANY.

ELECTRIC COUPLING.

No. 820,604.

Specification of Letters Patent.

Patented May 15, 1906.

Application filed June 1, 1905. Serial No. 263,211.

To all whom it may concern:

Be it known that I, OTTO SCHALLER, a subject of the King of Prussia, German Emperor, and a resident of Steglitz, near Berlin, Prussia, 5 Germany, have invented certain new and useful Improvements in Electric Couplings, of which the following is a description.

The present invention relates to electric couplings; and it consists of a single-pole coupling for connecting up the conductors between railway and other cars.

The object of the invention is to provide a coupling which can be handled by any ordinary workman without the slightest danger, 15 and this is attained by making the two coupling halves in the form of hermetically sealed or closed housings, having each an exterior contact-piece, which is, however, devoid of current as long as the coupling halves are out 20 of engagement, but which when the halves are connected together by means of the known bayonet-clutch thereon is connected up to the line-wires by mechanism inside the said housings and inaccessible from the exterior.

In order to render the present specification easily intelligible, reference is had to the accompanying drawings, in which similar letters of reference denote similar parts throughout 30 the several views.

Figure 1 shows the two halves of the coupling in engagement, the lower half being in longitudinal vertical section along the center line of the same. Fig. 2 is a plan view of one 35 half, and Fig. 3 a cross-section through one half on the line A B of Fig. 2, showing the interior contact in engagement, while Fig. 4 is a similar cross-section showing the parts out of engagement.

The coupling consists of the housings *a* and *b*, which may be connected together by means of the bayonet-clutches *c* and *c'*, this clutch being similar to the known clutches used in connection with the air-brake, steam-heating, 45 gas, and other plants. The two halves of the coupling are exactly alike in every respect, so that the description of one will enable the invention to be clearly understood. The cable *d* leads into the housing *b* and is 50 connected up to a contact-plate *e*, which is insulated from a downwardly-hanging carrier-yoke *g*, forming the upper part of the housing, and the bearing-rim for the diaphragm *m*, of any suitable material, which diaphragm must,

however, be movable. A contact-piece *l* is 55 fixed to the center of the diaphragm, or thereabout, and is screwed or otherwise fixed to downwardly-extending curved arms *n* within the housing. These arms are insulated at *r* from the central downwardly-extending part of the contact-piece *l*, which extension *s* carries a cross-pin *h* for the purpose hereinafter set forth. The insulated plate *e* has downwardly-extending plates *f*, slotted at *f'* to receive the ends of the pin *h*, and to 60 these plates are pivoted at *o o* two outwardly-extending lever-arms *i i*, connected up by means of a spring *j*, having the tendency to pull their outer ends toward each other. A strong spring *k* is mounted within the yoke *g* 65 and insulated therefrom, the said spring bearing against the under side of the part *l* and holding it in the position shown in Fig. 4 when the coupling is disengaged. This spring is 70 advantageously so strong that it cannot be 75 compressed by hand by the workman, and even if this were possible no danger could arise, since the coupling is a single-pole coupling.

The device operates in the following manner: When the bayonet-clutches of the two coupling halves are in engagement, as shown at Fig. 1, the springs *k* of each half will be depressed, and the pin *h* will consequently be lowered, turning up the outer ends of the 80 arms *i i* on their pivots *o o*. At the same time the arms *n n*, being depressed with the part *l*, will contact with the ends of the arms *i i* and connect up the conductors. In order to allow of proper contact of the arms *n n*, 85 Fig. 3, with the arms *i i*, the ends of the latter lever-arms are provided with slots *h'*, with which they engage over the pin *h*, so that the spring *j* will operate to pull the ends of the arms *i i* against and in contact with the arms 90 *n n*, as will be readily understood.

The interior mechanism of the coupling might be varied in a great many ways without departing from the spirit of the present invention, the main thing being to effect the 100 electrical connection within the closed housing after the coupling halves have been placed together.

I claim as my invention—

1. A coupling for electric conductors for 105 railway and other cars consisting of two similar single-pole coupling members having bayonet-clutches, each member constituting a

hermetically-sealed chamber having a projecting contact-piece normally devoid of current and means within each chamber for circuiting-in said contact-piece when the coupling members are in engagement.

5 2. A coupling for electric conductors for railway and other cars consisting of two similar single-pole coupling members having bayonet-clutches, each member constituting a hermetically-sealed chamber having a projecting contact-piece normally devoid of current a movable contact within each chamber connected up to the line-wire and adapted to connect with the projecting contact when the coupling members are in engagement.

10 3. A coupling for electric conductors for railway and other cars, consisting of two similar single-pole coupling members having bayonet-clutches, each member constituting an hermetically-sealed chamber, having a movable face to contact with the other member, a contact-piece projecting from said movable face a contact-piece within the chamber of each member adapted to complete the connec-

tion to the projecting contact-piece, when 25 the members are in engagement and means for holding the inner and outer contacts apart on the disengagement of the members.

4. A coupling for electric conductors for railway and other cars, consisting of two similar single-pole coupling members having bayonet-clutches, each member constituting a hermetically-sealed chamber, having a movable face to contact with the other member, a contact-piece projecting from said movable 30 face a contact-piece within the chamber of each member adapted to complete the connection to the projecting contact-piece, when the members are in engagement and a strong spring for holding the inner and outer contacts apart on the disengagement of the members.

15 In testimony whereof I affix my signature in the presence of two witnesses.

OTTO SCHALLER.
